UNITED STATES PATENT OFFICE.

WILLIAM CHESTERMAN, OF SHEFFIELD, ENGLAND.

TAPE-MEASURE.

SPECIFICATION forming part of Letters Patent No. 701,681, dated June 3, 1902.

Application filed November 16, 1901. Serial No. 82,548. (No model.)

To all whom it may concern:

Be it known that I, WILLIAM CHESTERMAN, a citizen of England, residing at Bow Works, Sheffield, in the county of York, England, have 5 invented a certain new and useful Improvement in Tape-Measures, (for which I have obtained a patent in Great Britain, dated May 14, 1901, No. 9,988,) of which the following is a specification.

10 In my British specification No. 16,252 of 1891 I have described a winding-handle and center for a measuring-tape, in which the handle is lifted by inserting the thumb-nail in a notch provided for the purpose. My 15 present invention consists in providing a more convenient and effective means for raising the handle, so that this can be done when the nail is weak or when a glove is worn by the operator, as I shall describe, referring to 20 the accompanying drawings.

Figures 1 and 2 are respectively a plan and a section of the central part of the tape, showing the winding-handle folded down when not in use. Figs. 3 and 4 are similar views showing the handle open and ready for use for 25 winding the tape. Fig. 5 is a detail section showing the spring for retaining the handle in its closed position.

The handle consists of a knob *a*, projecting 30 from a disk *b*, which is hinged to the shell of the handle. From the disk *b* a lever-arm *c* projects beyond the hinge, and under this arm *c* part of the shell of the handle is slotted out to give room for its movement. On press-

ing the arm *c* downward the disk *b*, with its 35 knob *a*, is caused to rise sufficiently to allow the fingers to open it out to the position for use. When the handle is closed, the disk *b* is held in position by a pair of springs, preferably made in one piece, which prevent the 40 handle from opening out of itself, but which readily yield when pressure is applied to the arm *c*.

The parts marked *d* represent the case of leather or other material to which the bushes 45 *e* are attached.

Having thus described the nature of my said invention and the best means I know of carrying the same into practical effect, I 50 claim—

A tape-measure having a case with a winding-reel therein, and a tilting handle pivoted to a hinge-pin on the reel, said handle when closed being substantially flush with the case, and having a lever-arm projecting to the rear 55 of the hinge-pin, so as to form an opening thumb-piece for the handle when closed, the case having a recess to allow the extension to be pressed downwardly; substantially as described. 60

In testimony whereof I have hereunto set my hand in presence of two subscribing witnesses.

WILLIAM CHESTERMAN.
